(57) **CLAIM**

The ornamental design for a squeeze to open container, as shown and described.

DESCRIPTION

FIG. 1 is a top, rear and left perspective view of the first embodiment of a squeeze to open container showing our new design in a closed configuration;
FIG. 2 is a bottom, rear and right perspective view thereof;
FIG. 3 is a left elevational view thereof;
FIG. 4 is a front elevational view thereof;
FIG. 5 is a rear elevational view thereof;
FIG. 6 is a right elevational view thereof;
FIG. 7 is a top plan view thereof;
FIG. 8 is a bottom plan view thereof;
FIG. 9 is a top, rear and right perspective view of a second embodiment of a squeeze to open container in an open configuration;
FIG. 10 is a bottom, rear and right perspective view thereof;
FIG. 11 is a left elevational view thereof;
FIG. 12 is a front elevational view thereof;
FIG. 13 is a rear elevational view thereof;
FIG. 14 is a right elevational view thereof;
FIG. 15 is a top plan view thereof; and,
FIG. 16 is a bottom plan view thereof.

The broken lines in the figures depict portions of the squeeze to open container that form no part of the claimed design. The solid lines around the middle of the squeeze to open container illustrate symbolic breaks. The appearance of any portion of the article between the break lines forms no part of the claimed design.
